U.S. PATENT DOCUMENTS

PP30,564 P3 6/2019 Whitaker

Primary Examiner — Keith O. Robinson*(74) Attorney, Agent, or Firm* — Foley & Lardner LLP

(57) **ABSTRACT**

This invention relates to a new and distinct variety of strawberry plant named 'SB_14_169-039'. This new strawberry plant named 'SB_14_169-039' is primarily adapted to the growing conditions of West Central Florida, and is primarily characterized by its achenes typically set even with the surface of the fruit, firm fruit, high marketable yield, early time of first flower and fruit, and very large berry size.

4 Drawing Sheets

1

Latin name of the genus and species of the plant claimed:
Fragaria ananassa.
Variety denomination: 'SB_14_169-039'.

BACKGROUND OF THE INVENTION

The present invention relates to a new and distinct strawberry variety named 'SB_14_169-039'. This new variety is a result of a controlled cross made in 2014 in an ongoing breeding program between the unpatented strawberry variety designated 'Red Merlin' as the seed (female) parent, and the unreleased, unpatented strawberry breeding selection designated 'BG_10_140-062' as the pollen (male) parent. The variety is botanically known as *Fragaria ananassa*.

The seedling resulting from the aforementioned cross was selected from a controlled breeding plot in Hillsborough County, Fla. in the fall/winter of 2015-2016. After its selection, the new variety was asexually propagated by stolons in both Siskiyou County, Calif. and San Joaquin County, Calif. The new variety was extensively tested over the next several years in fruiting fields in Hillsborough County, Fla. This propagation has demonstrated that the combination of traits disclosed herein as characterizing the new variety are fixed and remain true-to-type through successive generations of asexual reproduction.

BRIEF SUMMARY OF THE INVENTION

'SB_14_169-039' is primarily adapted to the climate and growing conditions of West Central Florida. The subtropical climate of West Central Florida provides the day length and moderate temperatures needed to produce an early yielding, vigorous plant and maintain fruit quality during the fall and winter production months.

2

The following traits have been repeatedly observed and are determined to be unique characteristics of 'SB_14_169-039', which in combination distinguish this strawberry plant as a new and distinct variety:

- 5 1. Achenes typically set even with the surface of the fruit;
  - 2. Firm fruit;
  - 3. High marketable yield;
  - 4. Early time of first flower and fruit; and
  - 5. Very large berry size.
- 10 'Florida Brilliance' (U.S. Plant Pat. No. 30,564) is currently the dominant strawberry variety in Hillsborough County, Fla. The fruits of 'SB_14_169-039' are lighter in color, slightly more elongated, and less firm. The achenes of 'Florida Brilliance' are more sunken than those of 'SB_14_169-039' and its plant architecture is larger in size and more open. In side-by-side comparisons from the 2021-2022 season (Nov. 23, 2021 to Feb. 25, 2022) 'SB_14_169-039' compares with 'Florida Brilliance' (U.S. Plant Pat. No. 30,564) in the following combination of characteristics as described in Table 1.

TABLE 1

Characteristic	'SB_14_169-039'	'Florida Brilliance' (U.S. Plant Pat. No. 30,564)
November marketable yield (gm/pit)	90	18
Season marketable yield (grm/plt)	666	562
November average berry size (gm)	24.5	20.8
Season average berry size (gm)	31.2	27.3
Average runners/plant	0.6	3.4

For identification, a series of molecular markers have been determined for this new variety.

‘SB_14_169-039’ compares with its parents, ‘Red Merlin’ and ‘BG_10_140-062’ by the following combination of characteristics as described in Tables 2 and 3.

TABLE 2

Characteristic	‘SB_14_169-039’	‘Red Merlin’
Fruit: size	Very Large	Medium
Fruit: marketable yield	High	Medium
Fruit: firmness	Firm	Very firm
Fruit: seed position	Even with surface	Slightly below to even with surface

TABLE 3

Characteristic	‘SB_14_169-039’	‘BG_10_140-062’
Fruit: size	Very Large	Very large
Fruit: marketable yield	High	Medium
Fruit: firmness	Firm	Firm
Fruit: seed position	Even	Even

BRIEF DESCRIPTIONS OF THE PHOTOGRAPHS

The accompanying color photographs illustrate the overall appearance of typical specimens of the new strawberry variety ‘SB_14_169-039’ at various stages of development, as true as it is reasonably possible with color reproductions of this type. Color in the photographs may differ slightly from the color value cited in the botanical descriptions which accurately describe the color of ‘SB_14_169-039’. The depicted plant and plant parts of the new strawberry variety ‘SB_14_169-039’ are approximately four months old. The photographs were taken in Hillsborough County, Fla.

FIG. 1 shows typical fruiting field characteristics of ‘SB_14_169-039’, taken in the month of February 2022;

FIG. 2 shows a close-up view of a typical plant of ‘SB_14_169-039’, taken in the month of February 2022;

FIG. 3 shows typical mature and immature field fruit of ‘SB_14_169-039’, taken in the month of February 2022; and

FIG. 4 shows typical internal and external mature fruit characteristics of ‘SB_14_169-039’, taken in the month of February 2022.

DETAILED BOTANICAL DESCRIPTION

The new variety ‘SB_14_169-039’ has not been observed under all possible environmental conditions. The characteristics of the new variety ‘SB_14_169-039’ may vary in detail, depending upon variations in environmental factors, including weather (temperature, humidity and light intensity), day length, soil type and location. In addition, the characteristics of any parental variety or comparison variety included in Table 1 of the present invention may vary in detail, depending upon variations in environmental factors, including weather (temperature, humidity and light intensity), day length, soil type and location.

The aforementioned photographs, together with the following description of the new variety ‘SB_14_169-039’, unless otherwise noted, are based on observations taken during the 2021-2022 growing season in Hillsborough

County, Fla. These measurements and ratings were taken from plants of ‘SB_14_169-039’ dug from a high-elevation nursery located in Siskiyou County, Calif. during mid-September 2021 and planted approximately four to five days later in Hillsborough County, Fla. The approximate age of the observed plants is four months. Yield observations including average weight and marketable yield, along with fruit quality characteristics including soluble solids, were measured during the 2021-2022 growing season. Flower measurements and characteristics are from secondary flowers unless otherwise noted. Fruit characteristics and measurements are from secondary fruit, unless otherwise noted.

Where noted, color terminology follows The Royal Horticultural Society Colour Chart, London (2015).

The following characteristics describe fruit, plant, stolon, foliage, fruiting truss, flower, reproductive organs and pest and disease characteristics of the new strawberry ‘SB_14_169-039’.

Fruit characteristics:

Color of mature fruit.—RHS N34A (orange-red group).

Color of internal flesh (excluding core).—RHS 36D (red group).

Color of core.—RHS 34A (orange-red group).

Average length (cm).—4.8.

Average width (cm).—4.2.

Size.—Very Large.

Average length/width ratio.—1.1 (ranges from as long as broad to slightly longer than broad).

Average calyx diameter (cm).—4.7.

Season average weight (gm).—34.9.

Achene color, shaded side.—RHS 173A (greyed-orange group).

Achene color, sun-exposed side.—RHS 161A (greyed-yellow group).

Average achene weight (mg).—<3.9.

Average achenes per berry.—253.

Average achene length (mm).—1.7.

Average achene width (mm).—1.0.

Season marketable yield (gm/plant).—910.

Predominant shape.—Conical.

Difference in shape between primary and secondary fruit.—Ranges from moderate to large.

Band without achenes.—Narrow.

Evenness of surface.—Mostly even.

Evenness of color.—Even.

Glossiness.—Strong.

Insertion of achenes.—Even.

Position of calyx attachment.—Inserted.

Attitude of sepals.—Outward.

Size of calyx in relation to fruit diameter.—Slightly Larger.

Adherence of calyx (when fully ripe).—Moderate.

Firmness of flesh (gf).—365.

Distribution of red color of the flesh.—Marginally and central.

Hollow center expression.—Weak.

Average cavity length (mm).—23.9.

Average cavity width (mm).—8.3.

Soluble solids (% brix).—5.8.

Time of first flowering.—Early (early to mid-October in Hillsborough County, Fla.).

Flowering season.—October-February.

Time of first fruit.—Early (mid-November in Hillsborough County, Fla.).

Fruiting season.—November-March.

<i>Post-harvest fruit longevity.</i> —9-11 days if stored according to industry standards.	5	<i>Stipule characteristics:</i>
<i>Type of bearing.</i> —Not remontant.		<i>Color.</i> —RHS 145B (yellow-green group).
Plant characteristics:		<i>Anthocyanin coloration.</i> —RHS 182C (greyed-red group).
<i>Average height (cm).</i> —24.0.	5	<i>Anthocyanin intensity.</i> —Weak.
<i>Average spread (cm).</i> —32.2.		<i>Average length (mm).</i> —34.8.
<i>Size.</i> —Medium.		<i>Average width (mm).</i> —8.9.
<i>Habit.</i> —Semi-upright.		<i>Base descriptor.</i> —Truncate.
<i>Density.</i> —Medium/High.	10	<i>Apex descriptor.</i> —Obtuse.
<i>Vigor.</i> —Medium.		<i>Shape.</i> —Triangular.
Stolon characteristics:		<i>Margin.</i> —Smooth.
<i>Color.</i> —RHS N144D (yellow-green group).		<i>Texture.</i> —Smooth.
<i>Anthocyanin coloration.</i> —RHS 174C (greyed-orange group).	15	Fruiting truss characteristics:
<i>Anthocyanin intensity.</i> —Weak.		<i>Anthocyanin coloration.</i> —N/A.
<i>Pubescence.</i> —Medium.		<i>Anthocyanin intensity.</i> —N/A.
<i>Attitude of hairs.</i> —Slightly Outward.		<i>Pubescence.</i> —Medium.
<i>Average quantity in nursery (per square foot).</i> —10.3 (medium).	20	<i>Secondary fruiting truss average length at maturity (cm).</i> —19.5.
<i>Average diameter at the bract (mm).</i> —2.8 (medium).		<i>Attitude at first pick.</i> —Prostrate.
<i>Average length (cm).</i> —30.6.		<i>Position relative to foliage.</i> —Ranges from level with to below.
Terminal leaflet characteristics:		<i>Flower quantity (average per plant season long).</i> —50.5 (high).
<i>Color of upper surface.</i> —RHS 147A (yellow-green group).	25	<i>Average fruits per truss.</i> —9.5.
<i>Color of underside.</i> —RHS 147B (yellow-green group).		<i>Pedicel attitude of hairs.</i> —Strongly upward.
<i>Average length (cm).</i> —7.5.		<i>Average pedicel length (cm).</i> —15.8.
<i>Average width (cm).</i> —7.4.		<i>Average pedicel diameter (mm).</i> —2.0.
<i>Average area terminal (cm²).</i> —55.5.	30	<i>Pedicel texture.</i> —Smooth.
<i>Average length/width ratio.</i> —1.01 (as long as broad to very slightly longer than broad).		<i>Pedicel color.</i> —RHS 144B (yellow-green group).
<i>Shape of base.</i> —Obtuse.		<i>Average peduncle length (cm).</i> —4.9.
<i>Margins (shape of teeth).</i> —Serrate to crenate.		<i>Average peduncle diameter (mm).</i> —3.0.
<i>Average serrations per leaf.</i> —18.3.	35	<i>Peduncle texture.</i> —Smooth.
Foliage characteristics:		<i>Peduncle color.</i> —N/A.
<i>Color of upper surface.</i> —RHS 147A (yellow-green group).		Flower characteristics:
<i>Color of underside.</i> —RHS 147B (yellow-green group).		<i>Flower bud shape.</i> —Pyriform.
<i>Number of leaflets.</i> —3.	40	<i>Average flower bud length (mm).</i> —17.8.
<i>Leaf size.</i> —Medium.		<i>Average flower bud diameter (mm).</i> —7.3.
<i>Average length (cm).</i> —10.4.		<i>Flower bud color.</i> —RHS 146B (yellow-green group).
<i>Average width (cm).</i> —13.1.		<i>Flower depth (mm).</i> —9.9.
<i>Average area foliage (cm²).</i> —135.6.	45	<i>Corolla (flower) average diameter (mm).</i> —30.5 (ranges from medium to large).
<i>Shape in cross section.</i> —Slightly concave.		<i>Upper petal color.</i> —RHS NN155A (white group).
<i>Texture/interveinal blistering.</i> —Medium.		<i>Lower petal color.</i> —RHS N155D (white group).
<i>Leaf glossiness.</i> —Medium.		<i>Petal shape.</i> —Orbicular.
<i>Leaf variegation.</i> —Absent.		<i>Petal apex descriptor.</i> —Rounded.
<i>Venation pattern.</i> —Pinnate.		<i>Petal margin.</i> —Smooth.
<i>Apex descriptor.</i> —Obtuse.	50	<i>Petal base.</i> —Decurrent.
<i>Secondary leaflet average length (cm).</i> —7.1.		<i>Petal texture.</i> —Smooth.
<i>Secondary leaflet average width (cm).</i> —7.4.		<i>Petal average length (mm).</i> —13.6.
Petiole characteristics:		<i>Petal average width (mm).</i> —13.1.
<i>Petiole color.</i> —RHS N144C (yellow-green group).	55	<i>Petal average length/width ratio.</i> —1.04 (as long as broad to slightly longer than broad).
<i>Average length (cm).</i> —13.6.		<i>Average petals per flower.</i> —5.7.
<i>Average diameter (mm).</i> —3.0.		<i>Relative position of petals (flowers with 5 or 6 petals).</i> —Overlapping.
<i>Petiolule color.</i> —RHS 144C (yellow-green group).		<i>Upper sepal color.</i> —RHS 139A (green group).
<i>Petiolule average length (mm).</i> —7.2.		<i>Lower sepal color.</i> —RHS 138B (green group).
<i>Average petiolule diameter (mm).</i> —2.1.	60	<i>Sepal shape.</i> —Cuneate.
<i>Attitude of hairs.</i> —Strongly outward.		<i>Sepal apex descriptor.</i> —Obtuse.
<i>Texture.</i> —Moderately Smooth.		<i>Sepal margin.</i> —Serrate.
<i>Frequency of bract leaflets.</i> —Ranges from 0 to 2 (50% occurrence).		<i>Sepal texture.</i> —Moderately Smooth.
<i>Size of bract leaflets.</i> —Small to Large.	65	<i>Sepal average length (mm).</i> —15.5.
<i>Pubescence.</i> —Light.		<i>Sepal average width (mm).</i> —7.5.
		<i>Sepal average length/width ratio.</i> —2.5.
		<i>Average sepals per flower.</i> —12.1.

Calyx average diameter (mm).—36.5.
Size of calyx relative to corolla.—Larger.
Size of inner calyx relative to outer calyx.—Smaller.
 Reproductive organs:
Receptacle color.—RHS 149D (yellow-green group).
Pollen color.—RHS 17A (yellow-orange group).
Stamen.—Present.
Average filament length (mm).—2.6.
Filament color.—RHS 1D (green-yellow group).
Average anther length (mm).—1.2.
Anther shape.—Ovoid.
Anther color.—RHS 17A (yellow-orange color).
Average pistils per flower.—253.
Pistil length (mm).—1 to 2.
Style length (mm).—0.5 to 1 mm.
Style color.—RHS 1D (green-yellow group).
Stigma diameter (mm).—<0.1.

Stigma shape.—Simple.
Ovary color.—RHS 149C (yellow-green group).
Pollen amount.—Abundant.
 Disease and pest reactions:
 5   *Colletotrichum crown rot (Colletotrichum gloeosporioides).*—Susceptible.
Fusarium wilt (Fusarium oxysporum).—Resistant.
Pestalotia leaf spot and fruit rot (Neopestalotiopsis sp.).—Moderately Susceptible.
 10   *Phytophthora crown rot (Phytophthora cactorum).*—Moderately Susceptible.

We claim:

1. A new and distinct strawberry plant named
 15 'SB_14_169-039', as herein described and illustrated by the
 characteristics set forth above.
